UNITED STATES PATENT OFFICE.

CHRISTIAN F. HEINKEL, OF CLEVELAND, OHIO.

CUTTING-TOOL.

1,106,561.

Specification of Letters Patent. Patented Aug. 11, 1914.

Application filed February 8, 1909. Serial No. 476,787.

To all whom it may concern:

Be it known that I, CHRISTIAN F. HEINKEL, a citizen of the United States, residing at Cleveland, in the county of Cuyahoga and State of Ohio, have invented a new and useful Improvement in Cutting-Tools, of which the following is a specification.

My invention relates to adjustable cutting tools in which the adjustment of the cutters is accomplished by means of a threaded engagement between the cutters and the adjusting means.

The object of my invention is: an inexpensive cutting tool which has a wide range of adjustment, and in which the cutters can be renewed at small expense. I attain this object by mounting the cutters which are made of a better grade of material in a body which is made of an inferior grade of material, or by securing the cutters upon one or more cutter blocks and mounting such cutter block or cutter-blocks in the body, the cutters having a threaded and operative engagement with an adjusting means.

In the accompanying drawings: Figure I is a side view of a cutting tool, partly broken away to show one arrangement of cutters and adjusting means. Fig. II is a section on line *c*—*c* of Fig. I. Fig. III is a section on line *b*—*b* of Fig. I, showing a clamping device. Fig. VI is a side view of a cutting tool, partly broken away to show another arrangement of cutters and adjusting means. Fig. V is a section on line *h*—*h* of Fig. IV. Fig. VI is a side view of a cutting tool, partly broken away to show an arrangement of cutters, adjusting means, lock nut, and retaining nut. Fig. VII is a side view of a cutting tool, partly broken away to show a cutting tool, partly broken away to show an arrangement of cutters, adjusting means, and lock nut. Fig. VIII is a side view of a cutting tool partly broken away to show an arrangement of cutters, adjusting means, and lock nut. Fig. IX is a side view of a cutting tool, partly broken away to show another arrangement of cutters, adjusting means, and lock nut. Fig. X is a side view of a cutting tool, partly broken away to show another arrangement of cutters, adjusting means, and lock means. Fig. XI is a side view of a cutting tool, partly broken away to show another arrangement of cutters, adjusting means, and locking means. Fig. XII is a side view of a cutting tool, partly broken

away to show an arrangement of cutters mounted on a cutter block, adjusting means, and locking means. Fig. XIII is a section on line *j*—*j* of Fig. XII, showing a method of securing the cutter block to the body. 60 Fig. XIV is a partial section, showing another arrangement of mounting cutters on a cutter block, adjusting means, and locking means. Fig. XV is a side view of a cutting tool, partly broken away to show another arrangement of cutters, adjusting means, and locking means. 65

Similar numerals refer to similar parts throughout the several views.

A general perusal of the drawings will 70 show that the spirit and intent of this invention is: a plurality of cutters which are adjustable simultaneously, inward or outward, by means of a threaded engagement between an adjusting means and said cutters. It will be noted that many modifications of construction can be devised which employ the spirit and intent of this invention. I therefore, and in order to clearly illustrate and have the spirit and intent of 80 this invention thoroughly understood, have shown several modifications in the drawings and will describe same, generally only, in this specification.

Referring particularly to cutting tool 85 shown in Figs. I and II; this consists of a body 13, of cutters 14, of adjusting cone 15, of retaining nut 16, and of clamping devices *y*. Body 13 has a central and circular opening 17 adapted to receive a shank, and 90 projections 18 which have grooves 19 adapted to receive cutters 14; said projections further have suitable openings adapted to receive clamping devices *y* shown in Fig. III. Body 13 further has a conical-mouth 20, the 95 cone face of which is somewhat back of the bottom of the thread on the side of cutters 14 so that adjusting cone 15 will not press against said cone face when retaining nut 16 is tight. Body 13 further has a tubular 100 projection 21 which is plain part way to receive adjusting cone 15, and threaded part way to receive retaining nut 16. Body 13 further has projection 22 which has a slot 23 for the purpose of keying this tool to a 105 shank. Cutters 14 have one side beveled and fit into grooves 19, the other side is threaded and adapted to engage adjusting cone 15. Said beveled sides are for the purpose of forming a wedge-shaped seat for the 110

cutters 14 whereby said cutters are forced upon their seats and chatter of the tool is prevented. Adjusting cone 15 has a central and circular opening adapted to fit the plain portion of projection 21, and a cone face 24 which is threaded and adapted to engage the threaded side of cutters 14. Adjusting cone 15 further has a counterbore to receive retaining nut 16, and means for rotating said adjusting cone, as for instance the spanner holes shown. Retaining nut 16 has a central and threaded opening adapted to threaded portion of projection 21, and means for its rotation as for instance the spanner holes shown.

Clamping device *y* is shown in Fig. III and consists of a tubular bushing 6 and a clamping screw 7. Each tubular bushing 6 which fits into an opening provided for that purpose in body 13, has a flat and beveled spot 12 adapted to fit the beveled side of cutters 2, and has a central opening to receive clamping screw 7. In order to adjust this tool, release screws 7 and rotate adjusting cone 15 until cutters 14 move in or out to the required size, then tighten screws 7 and the tool will be ready for use. In this tool, retaining nut 16 may be used to tighten or clamp cutters 14 as well as retaining adjusting cone 15; clamping device *y* may then be omitted.

Referring particularly to the cutting tool shown in Figs. IV and V; this consists of body 40, of cutter blocks 41, of adjusting cone 42, and of lock nut 43. Body 40 has a central and circular opening 44 to receive a shank, and a projection on its rear end with slots 45 to key body 40 to said shank. Body 40 further has slots 46 to receive cutter blocks 41, and chip grooves 47. Body 40 further has, at one end, an enlarged portion to support cutter blocks 41. Adjacent to said enlarged portion body 40 has a plain portion to receive adjusting cone 42, and adjacent to said plain portion body 40 has a threaded portion to receive lock nut 43. Cutter blocks 41 fit into slots 46, and are threaded on one side. Cutters 48 are secured to cutter blocks 41, either by means of soldering, brazing, welding, casting, or any other means. Adjusting cone 42 has a central opening adapted to said plain portion on body 40, and a cone face which is threaded and adapted to engage said threaded side of cutter blocks 41. A suitable means for taking hold is provided, as for instance the spanner holes shown. Lock nut 43 has a central and threaded opening adapted to said threaded portion of body 40, and a suitable means for taking hold, as for instance the spanner holes shown. In order to adjust this tool, release lock nut 43, rotate adjusting cone 42 until the cutters reach the size required, then tighten lock nut 43 which also tightens adjusting cone 42, and the tool

is ready for use. It will be seen that, in this arrangement, the cutter blocks are threaded and engage the threads on the adjusting cone and that the cutters are not directly engaged by said threads, but are in operative connection with said threads by means of the cutter blocks.

Referring particularly to the tap shown in Fig. VI; this consists of body 49, of cutters 50, of adjusting cone 51, of lock cone 52, of lock nut 53, and of retaining nut 54. Body 49 has a central opening 55 to receive a shank, and a projection with slots 56 to key body 49 to said shank. Body 49 further has an enlarged portion which has slots 57 to receive cutters 50; adjacent to said enlarged portion, and in front thereof, body 49 has a plain portion to receive adjusting cone 51, and adjacent to said plain portion, body 49 has a threaded portion to receive retaining nut 54; adjacent to said enlarged portion, and in rear thereof, body 49 has a smaller and plain portion to receive lock cone 52, and adjacent to said plain portion body 49 has a threaded portion to receive lock nut 53. Cutters 50 fit slidingly into slots 57 and have one side threaded to engage the threaded cone face of adjusting cone 51. Cutters 50 are threaded on their cutting face to suit any general or particular pitch to be tapped. Adjusting cone 51 has a circular opening to fit over said plain portion of body 49, and a threaded cone face to engage said threaded side of cutters 50. Adjusting cone 51 further has a counterbore to receive retaining nut 54, and a projection 58 which is adapted to receive a wrench for the purpose of rotating adjusting cone 51. Lock cone 52 has a central opening to fit over said plain portion of body 49, and a plain cone face adapted to bear against the plain side of cutters 50. A suitable means for preventing rotation while tightening lock nut 53 is provided, as for instance the spanner holes shown. Lock nut 53 has a central and threaded opening to engage said threaded portion of body 49, and has means for its rotation, as for instance the spanner holes shown. Retaining nut 54 has a central and threaded opening to engage said threaded portion of body 49, and is adapted to said counterbore of adjusting cone 51. A suitable means for its rotation is provided in retaining nut 54. In order to adjust this tool, release lock nut 53, rotate adjusting cone 51 until the cutters are set to the required size, then tighten lock nut 53, and the tool is ready for use.

Referring particularly to the cutting tool shown in Fig. VII; this consists of body 59, of cutters 60, of adjusting cone 61, of lock cone 62, of sleeve 63, and of retaining nut 64. Body 59 has a central opening 65 to receive a shank, and a projection with slots 66 to key body 59 to said shank. Body 59 further

has an enlarged portion with slots 67 for cutters 60; adjacent to, and in front of said enlarged portion body 59 has a plain portion and a head 68 adapted to receive and retain 5 adjusting cone 61; adjacent to, and back of said enlarged portion body 59 has a plain portion to receive sleeve 63, and adjacent to the last said plain portion body 59 has a threaded portion to receive retaining nut 64. Cutters 60 fit slidingly into slots 67, and have one side threaded to engage the threaded cone face of adjusting cone 61. Adjusting cone 61 has a central opening and counterbore adapted to said plain portion and 10 head 68 of body 59, and a threaded cone face to engage said threaded side of cutters 60. Adjusting cone 61 further has a suitable means for its rotation, as for instance the spanner holes shown, and must, in this case, 15 be split or made in halves in order to be put into place. Lock cone 62 has a central and threaded opening to engage the threaded portion of sleeve 63, and a plain cone face which bears against the plain side of cutters 20 60. Lock cone 62 further has a means for its rotation, as for instance the spanner holes shown. Sleeve 63 has a central opening to fit said plain portion of body 59, and is threaded to engage said threaded opening in lock cone 62. A means for its rotation 25 is provided, as for instance the spanner holes shown. Retaining nut 64 has a central and threaded opening to engage said threaded portion of body 59, and a means for its rotation, as for instance the spanner holes shown. In order to adjust this tool, release lock cone 30 62, rotate adjusting cone 61 until cutters 60 are set to the required size, then tighten lock cone 62, and the tool is ready for use. This arrangement shows an application of a split adjusting cone.

Referring particularly to the cutting tool shown in Fig. VIII; this consists of body 69, of cutters 70, of adjusting ring 71, and 45 of lock nut 72. Body 69 has a central opening 73 to receive a shank, and a projection with a slot 74 to key body 69 to said shank. Body 69 further has an enlarged portion with slots 75 to receive cutters 70, and a somewhat 50 smaller portion 76 which serves as an abutment for cutters 70. Body 69 further has a plain portion to receive adjusting ring 71, and a threaded portion to receive lock nut 72. Cutters 70 have one side threaded to 55 engage the threaded face of adjusting ring 71. Adjusting ring 71 has a central opening to fit said plain portion of body 69, and a means for its rotation, as for instance the spanner holes shown. Adjusting ring 71 60 further has one perpendicular face threaded to engage said threaded side of cutters 70. It should be noted here that, although said threads are cut upon a face perpendicular to the axis of the tool or body and not upon a 65 cone face, said perpendicular face acts as a

cone face because the sides of said threads form cone faces; if a thread with parallel sides, or what is commonly called a square thread were employed here instead of the angular sided thread shown, the intent of 70 this invention would not be met and the cutters could not be held rigidly. Lock nut 72 has a central and threaded opening to engage said threaded portion of body 69, and a means for its rotation, as for instance the spanner holes shown. In order to adjust 75 this tool, release lock nut 72, rotate adjusting ring 71 until the cutters are set to the required size, then tighten lock nut 72 and the tool is ready for use.

Referring particularly to the cutting tool shown in Fig. IX; this consists of body 77, of cutters 78, of adjusting ring 79, and of lock nut 80. This tool is similar to the tool shown in Fig. VIII, except that adjusting ring 79 and lock nut 80 are in front, and that body 77 has a beveled abutment to suit the beveled side of cutters 78.

Referring particularly to the cutting tool shown in Fig. X; this consists of body 81, 90 of cutters 82, of adjusting sleeve 83, of adjusting cone 84, and of a clamping means. Body 81 has a suitable shank, and a recess adapted to receive adjusting sleeve 83. Body 81 further has a threaded projection 85 to receive said clamping means which consists of a washer and nut. Slots 86 are provided in outer part of body 81 to receive cutters 82. Cutters 82 have both ends beveled and threaded to engage the threaded cone faces 100 of adjusting sleeve 83 and adjusting cone 84, and fit slidingly into slots 86. Adjusting sleeve 83 fits into said recess in body 81, and has, on its larger portion, a threaded cone face to engage one of said threaded ends of cutters 82. Adjusting cone 84 has a central opening to fit adjusting sleeve 83, and a threaded cone face to engage the other of said threaded ends of cutters 82. Adjusting cone 84 is splined to adjusting sleeve 83 by 105 means of spline 108, so that it may slide endwise or longitudinally upon adjusting sleeve 83, but may not rotate independently of adjusting sleeve 83. Adjusting cone 84 further has a means for its rotation, as for instance the spanner holes shown. In order to adjust this tool, release locking means (nut on projection 85), rotate adjusting sleeve 83 and adjusting cone 84 until the cutters are set to the size required, then tighten 110 the clamping means and the tool is ready for use.

Referring particularly to the cutting tool shown in Fig. XI; this consists of body 87, of cutters 88, of adjusting sleeve 89, of adjusting ring 90, and of a clamping means. This tool is similar to the tool shown in Fig. X-except that the ends of cutters 88 are 125 square or perpendicular to the axis of the tool. The explanation of the adjustments 130

and arrangement of the threads hereinbefore given in connection with the description of Fig. VIII applies also to this tool.

Referring particularly to the cutting tool shown in Figs. XII and XIII; this consists of body 91, of cutter block 92, which in this case forms a body for the cutters, of cutters 93, of adjusting cone 94, of lock nut 95, and of means for securing said cutter block to said body, either rigidly or floatingly. Body 91 has a central slot adapted to receive cutter block 92, and a central opening 96, transverse to said slot, to receive said means for securing said cutter block to said body, which means consists of screw 97 which has a reduced portion 98 to receive block 99; said block 99 has two taper sides and two straight sides and is rotatably mounted upon the reduced portion 98. An opening 20 is provided in cutter block 92 and blocks 99 fit therein. Thus it will be seen that when rotating screw 97 one way block 99 will be forced into said opening in cutter block 92 and said cutter block will 25 be secured rigidly to the body; whereas when rotating screw 97 in the opposite direction block 99 will be forced out of said opening in cutter block 92 and said cutter block will be held floatingly in said body, 30 since the taper block moving out of a taper aperture must leave a space between said block and the walls of said aperture as shown in Fig. XIII, and which space allows cutter block 92 to move laterally or float. 35 Cutter block 92 fits into said central slot, has grooves 100 to receive cutters 93, and has a rectangular opening with two taper sides to receive block 99 as previously mentioned. Cutter block 92 further has a plain and 40 reduced portion to receive adjusting cone 94, and a reduced and threaded portion to receive lock nut 95. Cutters 93 fit slidingly into grooves 100 and have one side beveled and adapted to the beveled side of grooves 45 100, the other side of cutters 93 is threaded to engage the threaded cone face of adjusting cone 94. Adjusting cone 94 has a central opening to fit said reduced and plain portion of cutter block 92 and a threaded 50 cone face to engage said threaded side of cutters 93. A means for its rotation is provided, as for instance the spanner holes shown. Lock nut 95 has a central and threaded opening to engage said reduced 55 and threaded portion of cutter block 92, and further has a means for its rotation, as for instance the spanner holes shown.

The arrangement shown in Figs. XII and XIII may be modified as shown in Fig. 60 XIV; this tool can be used as a rigid tool only and will not float, and the securing means of Figs. XII and XIII may be omitted. Body 91^a is similar to body 91 except that the slot is narrower to accommodate 65 the narrower cutter block 92^a, and that a

threaded portion 91^b is provided thereon, but no threaded portion being provided on cutter block 92^a. Cutters 93^a are similar to cutters 93. Adjusting cone 94^a is similar to adjusting cone 94 except that conical portion 94^b is provided. Lock nut 95^a is similar to lock nut 95 except that a conical opening is provided to fit over the conical portion of adjusting cone 94^a. This arrangement of adjusting cone and lock nut will 70 lock the cutters and the cutter block at one operation. In order to adjust these tools, release lock nut 95 or 95^a, rotate adjusting cone 94 or 94^a until the cutters are set to the required size, then tighten lock nut 95 or 95^a 75 so and the tool is ready for use.

Referring particularly to the threading die shown in Fig. XV, this consists of body 101, of cutters 102, of adjusting ring 103, of lock nut 104, and of retaining nut 105. Body 101 has a suitable shank and a central recess 106 to allow the object worked upon to pass in. Body 101 further has an enlarged portion with slots 107 to receive cutters 102, and a threaded portion at its front end to receive retaining nut 105. Body 101 further has a plain portion to receive adjusting ring 103, and a threaded portion to receive lock nut 104. Cutters 102 fit slidingly into slots 107 and have one side 90 threaded to engage adjusting ring 103. Adjusting ring 103 has a central opening to fit said plain portion of body 101, and one threaded face to engage said threaded side on cutters 102. A means for its rotation is provided, as for instance the spanner holes shown. Lock nut 104 has a central and threaded opening to engage said threaded portion of body 101, and a means for its rotation as for instance the spanner holes 105 shown. Retaining nut 105 has a central and threaded opening to engage said threaded portion of body 101, and a means for its rotation, as for instance the spanner holes shown. The method of adjusting this tool should be easily understood from previous descriptions. The cutters of this tool may, of course, be placed angularly similar to previous description and illustration, as will be obvious to any one skilled in the art. Graduation may be provided on any of the tools so that the amount of adjustment may be read. It will be seen that either the adjusting-member, or the means for operating the adjusting-member, or both, are located 110 near the cutters or the front of the tool whereby convenient accessibility is attained. By such an arrangement, the tool may be adjusted while in the machine, thus saving 115 the time of removing the tool from the machine when adjusting the same.

The several modifications shown and described should enable anyone skilled in the art to make and use any or all of said modifications, as well as design, make and use 120

others which employ the spirit and intent of this invention.

It may be noted here, generally, that the body may have any suitable form; that any number of cutters or cutter blocks may be used; that the body of the cutters or cutter blocks may be placed at any angle to, or perpendicular to the axis of the tool; that the cutters or cutter blocks may be placed so that their cutting faces are either radial with the axis of the tool, or radial and at an angle with said axis, or at an angle with the diameter (Fig. V) and parallel with said axis, or at an angle with the diameter 15 and at an angle with said axis, or parallel with and in front or ahead of the diameter (as seen in Fig. XIII for instance) and parallel with said axis, or parallel with and in front or ahead of the diameter and at an 20 angle with said axis; or parallel with and back of the diameter (reverse or opposite of the location of cutter shown in Fig. XIII) and parallel with said axis, or parallel with and back of the diameter and at an 25 angle with said axis. When placing the cutters ahead of the diameter, a negative cutting-rake is given the cutters and such tools are best adapted for operating upon brass or similar materials. When placing the cutters back of the diameter, a positive cutting-rake is given to the cutters, similar to a cutter placed at an angle with the diameter; such tools are best adapted to operate upon 30 steel or similar materials. It is preferred 35 that the cutters are placed at an angle, either with the axis of the tool, or with the diameter of the tool, or with both the axis and the diameter. It may further be noted that the adjustment of said cutters or cutter blocks 40 may be accomplished either by an adjusting cone or by an adjusting ring having a threaded face or faces adapted and arranged to adjust the tool.

It will be seen that in all of the modifications shown the sides of said threads are angularly disposed in relation to the axis of the tool as well as to the direction of the pressure brought upon the cutters by the locking means when locking the tool; this 50 is for the purpose of producing a wedging action to lock the cutters firmly and prevent "lost motion."

I claim:

1. In a device of the character described,

the combination of a body having a plurality of slots inclined to the axis of said body, 55 a cutter mounted in each of said slots, each of said cutters having threads upon one edge, an adjusting-member carried by said body and having a conical screw-threaded surface thereon which is adapted to engage the threads upon said cutters, and means for locking said adjusting members in adjusted position; the sides of said threads being inclined with respect to the axis of said device 60 to form wedge-shaped seats for said cutters upon said adjusting-member. 65

2. In a device of the character described, the combination of a body having a plurality of slots, a cutter mounted in each of said 70 slots, the bottom of each of said slots being beveled to form a wedge-shaped seat for one edge of each of said cutters, one edge of each of said cutters being beveled to engage said beveled bottom of said slots, the edge 75 opposite side beveled edge being provided with threads, an adjusting-member having a screw-threaded surface thereon which is adapted to engage the threads upon said cutters, and means for locking the said members in adjusted position; the sides of said threads being inclined with respect to the axis of said device to form wedge-shaped seats for the threaded edge of said cutters 80 upon said adjusting-member. 85

3. In a device of the character described, the combination of a body having slots inclined to the axis of said body; a cutter mounted in each of said slots, each of said 90 slots having a beveled bottom to form a wedge-shaped seat for one edge of each of said cutters, each of said cutters having a beveled edge to engage said beveled bottom of said slots, each of said cutters being provided with threads upon the edge opposite 95 said beveled edge, an adjusting-member having a conical screw-threaded surface thereon which is adapted to engage said threads upon said cutters, and means for locking the said adjusting-members in adjusted position; the sides of said threads being inclined with respect to the axis of said device to form wedge-shaped seats for said cutters 100 upon said adjusting-member.
